US00D862322S

(12) **United States Design Patent** (10) Patent No.: **US D862,322 S**
(45) Date of Patent: ** Oct. 8, 2019

(54) **TRUCK HOOD UNIT**

(71) Applicants: **Jonathan S. Duncan**, Seattle, WA (US); **Amanda Koh**, Kenmore, WA (US); **Peter Vurpillat**, Seattle, WA (US); **Chris Small**, Seattle, WA (US); **Cameron Ellis**, Snohomish, WA (US); **Harry Waraich**, Newcastle, WA (US); **John Jackson**, Sammamish, WA (US); **Rebecca Kern**, Kent, WA (US)

(72) Inventors: **Jonathan S. Duncan**, Seattle, WA (US); **Amanda Koh**, Kenmore, WA (US); **Peter Vurpillat**, Seattle, WA (US); **Chris Small**, Seattle, WA (US); **Cameron Ellis**, Snohomish, WA (US); **Harry Waraich**, Newcastle, WA (US); **John Jackson**, Sammamish, WA (US); **Rebecca Kern**, Kent, WA (US)

(73) Assignee: **PACCAR INC**, Bellevue, WA (US)

(**) Term: **15 Years**

(21) Appl. No.: **29/644,096**

(22) Filed: **Apr. 13, 2018**

(51) LOC (12) Cl. **12-16**
(52) U.S. Cl.
USPC **D12/173**

CLAIM

The ornamental design of a truck hood unit, as shown and described.

DESCRIPTION

FIG. 1 is a perspective view of a truck hood unit showing our new design;

FIG. 2 is another perspective view thereof;

FIG. 3 is a top plan view thereof;

FIG. 4 is a front elevational view thereof;

FIG. 5 is a rear elevational view thereof and;

FIG. 6 is a left side elevational view thereof; and,

FIG. 7 is a right side elevational view thereof.

The portions of the truck hood unit shown in broken lines throughout the drawing view are for environmental and illustrative purposes and form no part of the claimed design.

1 Claim, 7 Drawing Sheets
